The ornamental design for a front panel for optical disk drive, as shown.

DESCRIPTION

FIG. 1 is a right top front perspective view of a front panel for optical disk drive showing my new design;

FIG. 2 is a front elevational view thereof;

FIG. 3 is a left top rear perspective view thereof;

FIG. 4 is a left side elevational view thereof;

FIG. 5 is a right side elevational view thereof;

FIG. 6 is a top plan view thereof; and,

FIG. 7 is a bottom plan view thereof.
